(57) **CLAIM**

The ornamental design for a path light as shown and described.

DESCRIPTION

This application is related to commonly assigned, co-filed U.S. design patent application Ser. No. 29/792,009, filed on Feb. 25, 2022, by Adami et al., entitled "Lighting Fixture"; commonly assigned, co-filed U.S. design patent application Ser. No. 29/792,011, filed on Feb. 25, 2022, by Adami et al., entitled "Lighting Fixture"; commonly assigned, co-filed U.S. design patent application Ser. No. 29/792,012, filed on Feb. 25, 2022, by Adami et al., entitled "Bench"; and commonly assigned, co-filed U.S. design patent application Ser. No. 29/792,014, filed on Feb. 25, 2022, by Adami et al., entitled "Bench End", which applications are incorporated herein by reference in their entireties.

FIG. 1 is a front right perspective view of a path light, according to the new design;

FIG. 2 is a front left perspective view thereof;

FIG. 3 is a rear left perspective view thereof;

FIG. 4 is a rear left perspective view thereof;

FIG. 5 is a rear right perspective view thereof;

FIG. 6 is a rear right perspective view thereof;

FIG. 7 is a front elevational view thereof;

FIG. 8 is a right side elevational view thereof;

FIG. 9 is a left side elevational view thereof;

FIG. 10 is a rear elevational view thereof;

FIG. 11 is a top view thereof;

FIG. 12 is a bottom view thereof;

FIG. 13 is a front right perspective view of an alternative embodiment of the path light, according to the new design;

FIG. 14 is a front right perspective view thereof;

FIG. 15 is a front left perspective view thereof;

FIG. 16 is a rear left perspective view thereof;

FIG. 17 is a rear left perspective view thereof;

FIG. 18 is a rear right perspective view thereof;

FIG. 19 is a front elevational view thereof;

FIG. 20 is a right side elevational view thereof;

FIG. 21 is a left side elevational view thereof;

FIG. 22 is a rear elevational view thereof;

FIG. 23 is a top view thereof; and,

FIG. 24 is a bottom view thereof.

(Continued)

The broken lines in the drawings illustrate portions of the path light which form no part of the claimed design.
